UNITED STATES PATENT OFFICE

2,188,483

CAR MOVER

Carl E. Peterson, Long Beach, Calif.

Application September 26, 1938, Serial No. 231,764

2 Claims. (Cl. 254—38)

This invention relates to an improvement in car movers, and one object of my invention is to provide a novel car mover, in which a novel combination of leverages is applied to the wheel 5 of the railroad car for the purpose of moving the car.

Another object is to provide a novel car mover in which great leverage can be applied to the wheel of the railroad car to effectively move this car with a minimum effort on the part of the workman.

A feature of my invention is to provide a novel means of holding the car mover against retraction while in use, thus enabling the full force 15 to be applied to the wheel of the car, and without any slippage occurring in the car mover.

Other objects, advantages and features of my invention may appear from the accompanying drawing, the subjoined detailed description, and 20 the appended claims.

In the drawing—

Figure 1 is a side view of the car mover in operative position.

Figure 2 is a top plan view of the car mover.

Figure 3 is a side elevation of the lever.

Figure 4 is a fragmentary side elevation of the front portion of the base.

Referring more particularly to the drawing, the numeral 1 indicates the wheel of the railroad 30 car, which is to be moved, this wheel resting on the usual rail 2. The car mover 3 consists of a base casting or shoe 4. The front end of the shoe 4 is tapered so that it extends under the wheel 1, substantially as shown in Figure 1. The 35 forward end of the shoe acts as a pinch bar to assist in moving the wheel 1, as will be further described. A bar 5 is pivotally attached at 6 to the base 4—that is a pin extends through the base and through the bar, thus providing a bearing for the bar. The forward end of the bar 5 is 40 preferably turned upwardly, as shown at 7, so that the bar will more effectively engage the rim of the wheel 1. The shoe 4 is bifurcated, as shown at 8, thereby receiving the bar 5 between the bifurcations, and permitting the shoe and the bar to act in substantial alignment on the wheel of the railroad car when moving the same. A main lever 9 is pivotally attached to the rear 45 end of the shoe 4. A link 10 extends from the main lever 9 to the rear end of the bar 5, and is pivotally connected to both the lever and the bar.

The lower surface 11 of the shoe 4 is preferably curved, and a spur 12 is fixedly mounted on the shoe 4 forwardly of the pivot 6. The spur 12 is preferably a rectangular bar, which extends transversely of the shoe, and an edge of the bar projects downwardly and engages the rail 2 to prevent retraction of the car mover when in use. In operation, the car mover is first placed in the position shown in Figure 1. On downward movement of the lever 9 by the operator, the shoe 10 will rock over the spur 12, thus bringing the front end of the shoe into engagement with the wheel of the railroad car, and exerting the force against this wheel. When further force is exerted on the lever 9 by the operator, the bar 5 will tend to be swung downwardly, thus pressing the end 7 against the wheel of the railroad car, and exerting a further rotative force on the wheel. As soon as the spur 12 is placed forwardly of the pivot 6, a further and effective 20 leverage is provided, so that the operator can move a railroad car of great weight.

Having described my invention, I claim:

1. A car mover including a shoe adapted to rest on a railroad rail, the surface of the shoe 25 adapted to rest on the rail being convexly curved from the front to the rear thereof, a main operating lever pivotally attached to the rear of the shoe, a bar pivotally mounted in the shoe and arranged below the operating lever, the forward end of said bar being adapted to engage a wheel of the car, a link connecting the operating lever and the bar and pivotally attached to each, and a spur on the shoe, said spur being positioned forwardly of the bar pivot.

2. A car mover including a shoe adapted to rest on a railroad rail, the surface of the shoe 30 adapted to rest on the rail being convexly curved from the front to the rear thereof, a main operating lever pivotally attached to the rear of the shoe, a bar pivotally mounted in the shoe and arranged below the operating lever, said shoe being bifurcated and adapted to receive the bar between the bifurcations, a pivot pin extending through the shoe and the bar, the forward end 40 of said bar being adapted to engage a wheel of the car, a link connecting the operating lever and the bar and pivotally attached to each, and a spur on the shoe, said spur being positioned forwardly of the bar pivot.
